UNITED STATES PATENT OFFICE.

ANDREW S. HALLIDIE, OF SAN FRANCISCO, CALIFORNIA.

CLIP FOR WIRE-ROPE WAYS.

SPECIFICATION forming part of Letters Patent No. 357,664, dated February 15, 1887.

Application filed September 29, 1886. Serial No. 214,833. (No model.)

To all whom it may concern:

Be it known that I, ANDREW S. HALLIDIE, of the city and county of San Francisco, State of California, have invented an Improvement 5 in Clips for Wire-Rope Ways; and I hereby declare the following to be a full, clear, and exact description of the same.

My invention relates to a means for attaching the conveyer or carrier of an endless-wire-rope way to the traveling wire rope, the same being employed as an aerial ropeway.

It consists of a clip formed by inserting a short bar or shank within the rope in place of the central core, and a thin plate secured to 15 said bar and extending outward through the space between two strands and re-enforced or strengthened, so that the bucket or conveyer may be attached to this plate and suspended from the rope.

20 Referring to the accompanying drawings for a more complete explanation of my invention, Figure 1 is an end view showing a transverse section of the rope, with the core or shank and the connecting-plate. Fig. 2 is a plan of the rope 25 cut off transversely in line with the center of the suspending-plate, and showing one end of the bar which is inserted in the rope and the plate extending therefrom. Fig. 3 shows an 30 end view of the bucket, its suspending-arm, the rope, and the connecting link or plate. Fig. 4 is a side elevation of the same.

This invention is designed to be used in connection with what are known as "aerial rope-ways," and it is designed to take the place of 35 the band connection or clamp which has hitherto been used to attach the hanger by which the bucket or carrier is supported to the traveling rope.

In this invention, A is the rope or cable, 40 preferably made of wire, and in the present case shown as having six strands and a central core. B is a short bar or rod, made of about the same diameter as the central core, and having such a length that when it is placed 45 within the rope the strands will form a spiral extending partially around it from one end to the other sufficiently to prevent its being taken out between the strands. C is a thin blade or shank which is connected with the rod or bar 50 B, projecting outward from it, and standing at such an angle with the bar that it will pass

between any two strands of the rope, the angle of this plate being the same as the spiral formed by the strands. This plate may be attached to the bar by welding; or it may be 55 formed with it; or it may be formed in any suitable manner. It projects out to one side, as shown, having at its outer end the usual means for suspending the hanger, from the lower end of which the bucket or carrier is 60 sustained.

The ends of the rod or bar B are preferably arranged so that they will not mar or chafe the rope. When it is to be inserted into the 65 rope at any point, the strands are separated or the rope partially untwisted, and a sufficient portion of the core is removed to allow the bar B to be inserted in its place, the shank or blade C extending out between two strands of the rope, which is afterward twisted into 70 shape again, and as the position of the blade or shank C corresponds with the spiral twist of the strands of the rope, it will be manifest that it will pass out between the strands without separating them to an injurious extent. 75 At the same time the length of the bar B is such that the spirals of the strands will pass diagonally around it to a greater or less extent, and will thus prevent its slipping out between the strands. By this construction I 80 provide a very secure and effective method of connecting the bucket or carrier with the rope.

I am aware that in cable railways it has been suggested to connect two cables by cross-stops having their ends embedded within the 85 strands of the cables, with the portions of the cross-bars where they enter between the strands widened and made thinner, and I do not broadly claim this. As but one end of my clip is supported, it is necessary that it be 90 supported in the strongest manner possible by the strands of the wire rope, and by forming the clip at its junction with the metal core on an angle corresponding to the twist of the strands I secure a clamping effect upon the 95 metal of the plate C in addition to the hold of the strand upon the core B.

Having thus described my invention, what I claim as new, and desire to secure by Letters Patent, is—

1. An arm or clip connected at one end with a traveling-rope way, as shown, in combination

with a hanger or carrier supported from the other end, substantially as described.

2. A device for attaching a carrier or conveyer to an aerial traveling rope, consisting of an arm or plate having at one end a bar or shank which is fixed within the rope in place of the core, and at the opposite end a shaft at right angles with this bar, from which the carrier-arm depends, substantially as described.

10 3. A cylindrical piece of metal inserted into the center of a wire rope and in place of the core thereof, in combination with a thin plate

of metal projecting from the bar at an angle corresponding to the twist of the strands of which the rope is composed, whereby the said 15 plate is clamped by the strands, substantially as described.

In witness whereof I have hereunto set my hand.

ANDREW S. HALLIDIE.
